RAILWAY SIGNALING APPARATUS

Claude M. Hines, Pittsburgh, Pa., assignor to The
Union Switch & Signal Company, Swissvale,
Pa., a corporation of Pennsylvania

Original application June 23, 1939, Serial No.
280,731. Divided and this application April 12,
1940, Serial No. 329,317

5 Claims. (Cl. 171—119)

My invention relates to railway signaling apparatus; and it has particular reference to apparatus of the type employed in railway signaling systems of the class wherein coded trackway energy is utilized to control either or both wayside signals and train-carried cab signals.

This application is a division of my copending application, Serial No. 280,731, filed on June 23, 1939 for Railway signaling apparatus, now Patent No. 2,215,820 granted on September 24, 1940.

It has been proposed heretofore to employ saturation type relays, which are characterized by the fact that all the component parts thereof are stationary, as code following relays in connection with railway signaling systems utilizing coded trackway energy consisting of "on" periods when current flows and "off" periods when no current flows. I have found that when saturation type code following relays are employed to control the decoding apparatus of such systems, improved and more efficient operation of such decoding apparatus is effected by saturation relays having two or more output windings, by supplying the energy reproduced in each output winding of such relays to separate control elements or windings of the decoding apparatus. In this manner, the short-circuiting action of the rectifiers which convert into unidirectional current the alternating energy output of the saturation relay output winding is minimized, and as a result of the sharp cut-off in the reproduced coded energy supplied to the decoding apparatus, improved and more efficient operation of such apparatus is effected. Accordingly, an object of my present invention is the organization of railway signaling apparatus into novel and improved forms of railway signaling systems employing code responsive relays of the saturation type.

Another object is the provision of novel and improved forms of saturation type code following relays of the class broadly covered in a copending application, Serial No. 280,997, filed on June 24, 1939 by Bernard E. O'Hagan, for Railway signaling apparatus, and now Patent No. 2,215,821 granted on September 24, 1940.

Other objects and advantages of my invention will appear as the specification progresses.

I shall describe two forms of apparatus embodying my invention, and shall then point out the novel features thereof in claims.

In the accompanying drawing, Fig. 1 is a diagrammatic view showing one form of apparatus embodying my invention. Fig. 2 is a dia-

grammatic view illustrating a modified form of the saturation relay shown in Fig. 1.

Similar reference characters refer to similar parts in each of the two views.

5 Referring first to Fig. 1, the reference characters 1 and 1a designate the track rails of a stretch of electrified trackway over which traffic normally moves in the direction indicated in the drawing by an arrow, or from right to left as viewed in Fig. 1. The rails 1 and 1a are electrically separated by means of the usual insulated rail joints 2 into a plurality of successive adjoining track sections, of which only one section, 3—4, is shown complete in the drawing. 10 In accordance with the usual practice, impedance bonds 25 are provided one for each pair of insulated joints and which bonds conduct propulsion current flowing through the two track rails in parallel around the insulated joints, thereby enabling the track rails to form a portion of the return path of the propulsion current, but which bonds prevent the transfer around the insulated joints of the trackway or signaling current which flows through the two track 25 rails in series.

Each track section is provided with a signal, designated by the reference character S with a distinguishing suffix, located adjacent the entrance end of the section for governing traffic 30 operating thereover. Signals S may take any one of many suitable forms but in the form herein shown are three indication signals of the color light type, and each signal comprises a red lamp R, a yellow lamp Y and a green lamp 35 G, which lamps when illuminated indicate "stop," "caution" and "clear," respectively.

Each section is provided with means, located at the exit end of the section, for supplying to the rails of the associated section coded trackway or signaling energy. This trackway energy preferably is alternating current of a frequency different from the frequency of the propulsion current employed, and for the purposes of this application I shall assume that the trackway energy is alternating current of a frequency of 100 cycles per second. I shall describe in detail only the means supplying trackway energy to the rails at the exit end of the section lying to the right as viewed in the drawing, or in the rear of section 3—4, it being understood that the rails of section 3—4 are provided with trackway energy through the medium of similar apparatus which has been omitted from the drawing since it would be but a duplication of the

apparatus represented at the exit end of the section next in the rear of section 3-4.

The trackway energy transmitting apparatus, as shown, includes a track transformer, designated by the reference character TT with a suitably distinguishing suffix, having its secondary winding constantly connected across the track rails of the associated section adjacent its exit end; a source of alternating current of suitable frequency connected over one or another of a plurality of circuits to the primary winding of the track transformer TT; a coding device or coder, designated by the reference character CT with a suitably distinguishing suffix, for coding or interrupting periodically the current supplied to the transformer primary over the plurality of circuits; and control means for selectively rendering active one or another of the plurality of circuits over which the source of current is connected to the primary winding of the track transformer TT.

Each coding device CT is constantly supplied with energizing current from a suitable source of alternating current, not shown in the drawing but having its opposite terminals designated by the reference characters BX and CX, and each device constantly operates a plurality of contacts each at a different preselected rate. As shown in Fig. 1, coder CT4 is provided with two contacts 75 and 180, which contacts are periodically opened and closed at the rates of 75 and 180 times per minute, respectively.

Contact 180 of coder CT4 is interposed in one circuit over which alternating current is at times supplied to the primary winding of track transformer TT4, and this circuit may be traced from terminal BX of the source of 100 cycle alternating current, through contact 180 of coder CT4, front contacts 6, 30 and 31 of relays BSA and FSA, respectively, which relays will be referred to in more detail presently, and the primary winding of transformer TT4 to the other terminal CX of the source of 100 cycle alternating current. The current that is supplied to transformer TT4 over the above traced circuit is coded by contact 180 of coder CT4 at the 180 code rate, and this 180 code is utilized to provide a "clear" indication in a manner which will be made clear as the description proceeds.

When both relays BSA and FSA are released, contact 75 of coder CT4 is interposed in a circuit which extends from terminal BX through back contact 32 of relay BSA, back contact 33 of relay FSA, contact 15 of coder CT4, and the primary winding of transformer TT4 to terminal CX. The current supplied over the above traced circuit is coded at the 75 code rate by contact 75 of coder CT4 and this current is employed to provide a "caution" indication in a manner to be explained presently in detail.

When relay BSA is released and relay FSA is picked up, uninterrupted or non-coded alternating current is supplied to transformer TT4 over a circuit which passes from terminal BX through back contact 32 of relay BSA, front contact 31 of relay FSA, and the primary winding of transformer TT4 to terminal CX. The purpose of this non-coded trackway energy will be made clear as the description proceeds.

Each section is provided at its entrance end with a code responsive relay of what I shall term the saturation relay type, designated by the reference character DR with a suitably distinguishing suffix. Relay DR5 shown in Fig. 1 located at the entrance end of section 3-4 is an improved

form of a saturable transformer type relay, characterized by the fact that all its component parts are stationary.

Relay DR5 comprises a magnetizable core 8 having five legs 9, 10, 11, 12 and 12a, respectively, connected together at each end to form an integral relay core structure. A primary or local input winding 13 is disposed on the central leg 11 of the core, and this winding is constantly supplied with alternating current from a suitable source designated by the terminals BX and CX, for setting up a primary flux in core 8. As is readily apparent from an inspection of the drawing, this primary flux is provided with two parallel magnetic circuits or paths through the relay core, each path including as a common element leg 11 upon which winding 13 is carried. A first of the two paths includes, in addition to leg 11, the two legs 9 and 10 in parallel, and the adjoining top and bottom portions of the core; and the second of the two magnetic circuits includes leg 11, the two legs 12 and 12a in parallel, and the adjoining top and bottom portions of the core.

25 Relay DR5 also comprises two saturating windings 15 and 44 for controlling the relative reluctances of the two magnetic circuits of core 8. As herein shown, a first or biasing winding 44 of these two saturating windings comprises two coils 44a and 44b disposed one coil on each of the two parallel legs of a particular one of the two magnetic circuits of core 8. In the particular relay shown in Fig. 1, the two coils 44a and 44b are disposed on legs 12 and 12a, respectively, of the second magnetic circuit of the core, and these coils are connected in series in such manner that when supplied with unidirectional current of a preselected magnitude, the coils cooperate in circulating a unidirectional flux through legs 12 and 12a of core 8 of such value as to substantially magnetically saturate these legs. Preferably, the coils 44a and 44b are constantly supplied with unidirectional current of the preselected magnitude, and as shown this current may be supplied from a separate source of unidirectional current, such as a battery not shown but having its opposite terminals designated by the reference characters B and C, or if desired such current may be supplied from a source of alternating current through the medium of a rectifier. This constant energization of biasing winding 44 of relay DR5 normally causes the second magnetic circuit of core 8 including the two legs 12 and 12a to have a relatively high reluctance with respect to the reluctance of the other or first magnetic circuit, and as a result substantially all of the primary flux set up in the core due to current in winding 13 is caused normally to thread the first magnetic circuit.

60 The other or control winding 15 of the two saturation windings of relay DR5 comprises four coils 15a, 15b, 15c and 15d disposed one coil on each of the two parallel legs of the two magnetic circuits of core 8. These coils are connected in series in such manner that when the control winding is supplied with unidirectional current, the two coils of each pair of coils disposed on each of the two magnetic circuits of the core cooperate in circulating a flux through the two parallel legs of the associated circuit.

The control saturating winding 15 of relay DR5 is at times supplied with unidirectional current from the track rails 1 and 1a of its associated section, through the medium of a resonant

rectifier unit RU1, which has its input terminals connected across the rails of section 3-4 adjacent entrance end 4 and which has its output terminals connected across control winding 15 of relay DR5. The details of construction of unit RU1 are not shown in the drawing, but this unit usually includes a transformer, a capacitor and a reactor so arranged and proportioned that the 100 cycle trackway signal current is freely passed by the unit, but the propulsion current is blocked and is prevented from reaching the control winding of relay DR5. This unit also includes a rectifier, which functions to convert into unidirectional energy the 100 cycle alternating energy so that winding 15 of relay DR5 is supplied with unidirectional current from the track rails.

The magnitude of current supplied to winding 15 of relay DR5 from the track rails of section 3-4 through the medium of resonant rectifier unit RU1 is selected in such manner that due to the current in the two coils of each pair of coils disposed on each of the two circuits of core 8, there is created flux of a value sufficient to substantially saturate the two legs of each of the two magnetic circuits. The polarity of this current also is selected so that flux due to current in coils 15c and 15d is opposite in polarity to the flux due to current in coils 44a and 44b of the biasing winding, and as a result these fluxes substantially cancel each other. It can be seen, therefore, that when current is supplied to the control winding of relay DR5, legs 9 and 10 of the first magnetic circuit of the core become magnetically saturated, while a substantially zero resultant flux condition obtains in legs 12 and 12a of the second circuit, and under this condition, substantially all of the primary flux due to current in winding 13 threads the second magnetic circuit of core 8.

Relay DR5 further includes a plurality of output or secondary windings disposed on relay core 8 in inductive relation with input winding 13. As shown in Fig. 1, two output windings 14 and 23 are provided one on each magnetic circuit of the core. One of these output windings 14 includes two coils 14a and 14b disposed respectively on legs 12 and 12a of the second magnetic circuit of the core, and these coils are connected in series in such manner that when electromotive forces are induced therein due to primary flux threading legs 12 and 12a in parallel, such forces are additive. The other output winding 23 of relay DR5 includes two coils 23a and 23b disposed respectively on legs 9 and 10 of the core and connected in series in such manner that electromotive forces induced therein due to primary flux threading both legs 9 and 10 in parallel are additive.

With relay DR5 constructed in the manner just described, it is apparent that when biasing winding 44 of the relay is energized and no current is received from the rails of section 3-4 by control winding 15, substantially all of the primary flux due to current in winding 13 threads legs 9 and 10 of core 8. As a result, therefore, an electromotive force of relatively large magnitude is induced in output winding 23 and practically no current is induced in the other output winding 14. When, however, current is supplied from the rails to control winding 15, the flux due to current in winding 15 substantially saturates legs 9 and 10 and substantially all of the primary flux circulates through legs 12 and 12a since the flux due to current in coils 15c and 15d opposes and substantially cancels the flux due

to current in windings 44a and 44b. A relatively high electromotive force accordingly is induced in winding 14 and substantially no current is induced in winding 23 when control winding 15 of relay DR5 is energized. It follows, therefore, that an electromotive force of relatively large magnitude is induced in output winding 14 or output winding 23 according as control winding 15 of relay DR5 is or is not energized, and that the amplification ratio of the relay is relatively high. That is to say, the ratio of the magnitude of current that is induced in either output winding when under one condition of the control winding, the primary flux threads the associated magnetic circuit upon which the winding is mounted, to the magnitude of current induced in such winding when under the other condition of the control winding, the primary flux is shunted away from its associated circuit, is relatively large due to the fact that in the latter event substantially no electromotive force is induced in such winding. Relay DR5 accordingly has a relatively high amplification ratio; and windings 14 and 23 of this relay function as "front contact" and "back contact" windings in that electromotive forces are supplied from such windings when control winding 15 of relay DR5 is respectively energized or deenergized.

Relay DR5 is employed to control, in accordance with the rate at which the trackway energy received by its control winding 15 from the rails of section 3-4 is coded, the associated traffic controlling signal S4 and the supply of trackway energy to the rails of the section next in the rear of section 3-4. Control of signal S4 is established by relay DR5 through the medium of a decoding transformer DT4, and two signal control relays H4 and AJ4.

Decoding transformer DT4 shown in Fig. 1 is substantially similar in construction to the split-core decoding transformer shown in a copending application, Serial No. 213,016, filed on June 10, 1938 by Bernard E. O'Hagan for Railway traffic controlling apparatus, now Patent No. 2,215,823 granted on September 24, 1940. This transformer comprises two magnetizable cores 45 and 47 provided respectively with primary windings 46 and 48, and two secondary windings 49 and 50 which link both cores 45 and 47. Primary winding 46 is connected through the medium of a rectifier R7 to "back contact" output winding 23 of relay DR5, and primary winding 48 is connected through a rectifier R3 to "front contact" output winding 14 of relay DR5. The primary windings 46 and 48 are so arranged that the unidirectional fluxes which are set up in cores 45 and 47 when current is being supplied to these windings will thread the secondary windings in opposite directions, and in order to cause the flux to decay quickly in the cores 45 and 47 when the associated primary winding becomes deenergized in spite of the short-circuiting action of rectifiers R7 and R3, each core is provided with one or more air gaps 51, or their equivalent, two such air gaps being shown in the drawing because of the greater ease of assembly of the transformer which is afforded by this arrangement. Secondary winding 49 of transformer DT4 is connected across the input terminals of a rectifier R4, and the output terminals of this rectifier are connected over a front contact 27 of relay BSA to the terminals of signal control relay H4 so that relay H4 is picked up whenever coded current is supplied by relay DR5 to transformer DT4 and relay BSA is picked up.

The other winding 50 is connected through the medium of a decoding unit DU180 to relay AJ4. The details of construction of the decoding unit DU180 are not shown in the drawing, but this unit usually comprises a rectifier and a reactor condenser tuning unit tuned to resonance at a frequency corresponding to the 180 code, whereby relay AJ4 is effectively energized and is picked up when and only when 180 code is supplied by code following relay DR5 to decoding transformer DT4. 10

The relays AJ4 and H4 cooperate to selectively control the various aspects displayed by signal S4 in the following manner. When relays H4 and AJ4 are both picked up, signal S4 is caused to display its "clear" indication over a circuit which may be traced from terminal B through front contact 19 of relay H4, front contact 20 of relay AJ4 and the filament of lamp G of signal S4 to terminal C. When relay H4 is picked up and relay AJ4 is released, signal S4 then is caused to display its "caution" indication over a circuit passing from terminal B through front contact 19 of relay H4, back contact 22 of relay AJ4 and filament of lamp Y of signal S4 to terminal C. When, however, both relays H4 and AJ4 are released, signal S4 then is caused to display its "stop" indication over a circuit passing from terminal B through back contact 21 of relay H4, and the filament of lamp R of signal S4 to terminal C. 20

The previously mentioned relays BSA and FSA are slow releasing relays provided to cooperate with relay H4 in controlling the supply of trackway energy to the rails of the section next in the rear of section 3-4, and also to protect against false operation of signal S4 due to a failure of an insulated joint separating the rails of section 3-4 from the rails of the section next in the rear. Relay FSA is connected across the output terminals of rectifier R3 and accordingly is energized in response to current caused to be induced in winding 14 of relay DR5 when current is received by winding 15 of this relay from the rails of section 3-4, and the slow releasing characteristics of this relay, effected in part by a resistor 26 connected across its terminals, are selected to maintain its armature in its picked-up condition during the intervals between successive "on" periods of the 75 or 180 code. Relay FSA accordingly functions as a front contact repeater relay for relay DR5. Relay BSA is connected over a front contact 28 of relay FSA across the output terminals of rectifier R1 and it follows that relay BSA is energized in response to current supplied from "back contact" output winding 23 of relay DR5 if relay FSA also is picked up in response to current induced in "front contact" output winding 14 of relay DR5. The slow releasing characteristics of relay BSA which are effected in part by means of a resistor 29 connected across its terminals over front contact 28 of relay FSA, are selected to maintain the armature of relay BSA in its picked-up condition during the intervals between successive "off" periods of the 75 or 180 trackway code. 30

The above-mentioned apparatus embodying my invention functions to control the wayside signal S4 and the supply of coded energy to the rails of the section next in the rear of section 3-4 in the following manner: the rails of section 3-4 are supplied with 180 or with 75 code according as the section next in advance is unoccupied or occupied. When the rails of section 3-4 are supplied with 180 code and the section is unoccupied, all parts of the apparatus occupy the positions in 35

which they are shown in Fig. 1. Under such assumed conditions, relay FSA is held energized in response to the impulses of energy caused to be induced in winding 14 of relay DR5 by the coded energy received by winding 15 from the track rails, and with relay FSA picked up to close its front contact 28, relay BSA is held energized in response to the impulses of energy caused to be induced in winding 23 of relay DR5. Relay H4 accordingly is connected over front contact 21 of relay BSA to rectifier R4, and this relay is held picked up in response to current caused to be induced in winding 49 of transformer DT4 by the supply of current impulses from windings 14 and 23 of relay DR5 to primary windings 48 and 46 of transformer DT4. Also, since these impulses of current supplied to primary windings 48 and 46 of transformer DT4 are coded at the rate corresponding to the 180 code rate received by control winding 15 of relay DR5 from the track rails, the current impulses induced in secondary winding 50 of transformer DT4 are likewise coded at the rate corresponding to the 180 code rate and relay AJ4 is energized and picked up. The previously traced circuit for lamp G of signal S4 accordingly is completed, whereby that signal is caused to display its "clear" indication; and relays H4, BSA and FSA complete the previously traced circuit over which 180 code is supplied to the rails of the section next in the rear of section 3-4. 40

When section 3-4 is supplied with 75 code and the section is unoccupied, relays FSA, BSA and H4 are picked up but relay AJ4 is released. The rails of the section next in the rear of section 3-4 accordingly are still supplied with 180 code, but signal S4 is controlled to display its "caution" indication due to the illumination of lamp Y of this signal over its circuit completed at back contact 22 of relay AJ4 and front contact 19 of relay H4. 45

When a train occupies section 3-4, the trackway or signaling current is then shunted by the train away from relay DR5 so that relays FSA, BSA, H4 and AJ4 are all released. Signal S4 is controlled to display its "stop" indication due to the energization of lamp R; and 75 code is supplied to the rails of the section next in the rear of section 3-4 over the previously traced circuit including back contact 32 of relay BSA, back contact 33 of relay FSA and contacts 75 of coder CT4. The section next in the rear of section 3-4 is, therefore, supplied with 180 code at all times except when section 3-4 is occupied and it follows that the supply of current to the rails of a section is controlled by traffic conditions in advance of that section. 50

In the event that one or both of the insulated joints separating section 3-4 from the section next in the rear breaks down, the relays FSA and BSA function to protect against signal S4 displaying a false "clear" aspect. If, for example, the joint 2 located in rail 1 at the entrance end of section 3-4 breaks down due to the passage of a train through the section, the 75 code current that is supplied to the section in the rear of section 3-4 might leak forwardly over the defective joint. This current is provided with a return path around the intact joint 2 in rail 1a due to the autotransformer action of impedance bond 25, so that after the train has passed far enough into section 3-4 that a material length of rail is included in the train shunt of relay DR5, control winding 15 of this relay might become sufficiently energized to cause impulses of energy to 55

be induced in output windings 14 and 23 of relay DR5. However, relay FSA picks up on the first impulse of current supplied from relay DR5 under the assumed conditions, and with relay FSA picked up and relay BSA released, uninterrupted or non-coded alternating current is supplied to the rear section. This current, leaking forwardly over the defective joint, will constantly energize winding 15 of relay DR5 and cause a relatively large electromotive force to be steadily induced in winding 14, whereupon relay FSA is held energized and all other relays are deenergized. In this condition of the apparatus, signal S4 continues to display its "stop" indication. It can be seen, therefore, that there is avoided the possibility that relay H4 might pick up in response to coded current leaking forwardly over a defective joint, and in so doing control signal S4 to an improper aspect. In addition, if relay H4 had been employed to control the supply of 180 or 75 code to the rear section over its front and back contacts, respectively, as is the customary practice, then relay H4 in picking up falsely in response to the 75 code leaking forwardly over the defective joint would then have caused 180 code to be supplied to the rear section. This 180 code would then leak forwardly over the defective joint and cause relay AJ4 to pick up and thereby falsely control signal S4 to its "clear" aspect. It can be seen, however, that by utilizing relays FSA and BSA in the manner described, such false indications due to a failure of an insulated joint are prevented.

Referring now to Fig. 2, a modified form of the saturation relay illustrated in Fig. 1 is shown employed as a code repeater at a cut-section location. Relay DR4 shown in Fig. 2 is substantially similar to relay DR5 previously described, except for the fact that only one output winding 23 is employed and this winding is mounted on the two legs 12 and 12a of the core. In addition, the biasing winding 44 of relay DR5 of Fig. 1 has been replaced by another biasing winding 42 comprising two coils 42a and 42b mounted respectively on the two legs 9 and 10 of the core, and this winding is constantly supplied with unidirectional current through the medium of a rectifier R8 having its input terminals connected to a secondary winding 43 mounted on the center leg of the core in inductive relation with winding 13.

It is believed that the operation of relay DR4 will readily be apparent from an inspection of Fig. 2 together with the foregoing description of the operation of relay DR5 shown in Fig. 1, and further detailed description is believed to be unnecessary except to point out that the functions of output winding 23 and biasing winding 42 of relay DR4 are substantially similar to the functions of output winding 23 and biasing winding 44 of relay DR5. That is to say, biasing winding 42 of relay DR4 is constantly energized to create in legs 9 and 10 a biasing flux which normally causes the primary flux due to current in winding 13 to thread legs 12 and 12a and consequently induce in winding 23 a relatively high electromotive force. When, however, current is supplied from the track rails to control winding 15 of the relay, the flux due to current in coils 15c and 15d substantially saturates the legs 12 and 12a while the flux due to current in coils 15a and 15b opposes and substantially cancels the flux due to current in winding 42. The primary flux is shunted away from output winding 23 during the "on" period of the trackway code 75

and it follows that winding 23 functions as a "back contact" output winding of the relay.

When relay DR4 is employed at a cut section, as shown in Fig. 2, output winding 23 is connected across the track rails of the subsection into which the coded energy is to be cascaded, and control winding 15 of relay DR4 is connected through a resonant rectifier unit RU1a to the rails of the other or advance subsection. In this manner the trackway code that is received by the relay from the rails 1 and 1a of the advance subsection is repeated or cascaded into the rails of the other or rear subsection.

In addition to repeating the trackway code from one subsection to the next, relay DR4 also functions to supply non-coded or steady "clearing out" energy to the rails of the rear subsection. This non-coded "clearing out" energy is supplied by relay DR4 to the rails of a rear subsection whenever the advance subsection is occupied and the coded trackway energy is shunted away from the relay DR4, since under the conditions assumed, winding 15 of relay DR4 is constantly deenergized and as a result there is constantly induced in winding 23 of relay DR4 a relatively high electromotive force. This non-coded current is thus supplied from winding 23 to the rails of the rear subsection whenever the advance subsection is occupied, and it may be employed in the usual manner to control apparatus, such as highway crossing signal control apparatus, etc., which it is desired to be responsive only to traffic conditions in the rear of the two adjoining subsections.

35 Although I have herein shown and described only two forms of railway signalling apparatus embodying my invention, it is to be understood that various changes and modifications may be made therein within the scope of the appended claims without departing from the spirit and scope of my invention.

Having thus described my invention, what I claim is:

1. A relay of the saturation type comprising a 45 five-legged magnetizable core having two magnetic circuits both including a common central leg and two independent legs of said core, a primary winding disposed on the central leg of said core and normally supplied with alternating current, a saturation winding for controlling the reluctance of said two magnetic circuits and comprising four coils one disposed on each of the four independent legs of said core, said four coils being connected in series in such manner that the resultant voltage normally induced therein in response to said alternating current in said primary winding is substantially zero and being effective when supplied with unidirectional current of a given magnitude to magnetically saturate each of said two magnetic circuits, a biasing winding for modifying the saturating effect of said saturating winding on one but not the other of said two magnetic circuits and comprising two coils one disposed on each of the two independent legs of said one magnetic circuit, said two coils of said biasing winding being connected in series in such manner that when said two coils of the biasing winding are supplied with unidirectional current the magnetic flux created thereby opposes the magnetic flux created by the two coils of the saturation winding disposed on the said one magnetic circuit, and a secondary winding comprising two coils disposed on each of the two independent legs of one of said magnetic circuits, said two coils of said secondary winding

being connected in series in such manner that any voltages induced therein in response to the alternating current in said primary winding are additive.

2. A relay of the saturation type comprising a five-legged magnetizable core having two magnetic circuits both including a common leg and two independent legs of said core, a primary winding disposed on said common leg and normally supplied with alternating current, a saturation winding for controlling the reluctance of said two magnetic circuits and comprising four coils one disposed on each of the four independent legs of said core, said four coils being connected in series in such manner that no effective voltage is normally induced therein in response to said alternating current in said primary winding and being effective when supplied with unidirectional current of a given magnitude to magnetically saturate each of said two magnetic circuits, a biasing winding for opposing the saturating effect of said saturating winding on one but not the other of said two magnetic circuits and comprising two coils one disposed on each of the two independent legs of said one magnetic circuit, said two coils of said biasing winding being connected in series in such manner that when said two coils are supplied with unidirectional current the magnetic flux created thereby opposes the magnetic flux created by the two coils of the saturation winding disposed on the said one magnetic circuit, a first secondary winding comprising two coils one disposed on each of said two independent legs of said one magnetic circuit and connected in series in such manner that any voltages induced therein are additive, and a secondary winding comprising two coils one disposed on each of the two independent legs of the other of said magnetic circuits and connected in series in such manner that any voltages induced therein are additive.

3. A saturation relay characterized by the fact that all its component parts are stationary, comprising the combination of a five-legged magnetizable core structure having two magnetic circuits both including a common leg and two independent legs of said core, a primary winding disposed on said common leg for creating an alternating magnetic flux when supplied with current from a source of alternating current, a saturation winding effective when supplied with unidirectional current to control the reluctances of said two magnetic circuits and comprising four coils one mounted on each of the four independent legs of said core, said coils of the saturation winding being connected in series in such manner that the resultant electromotive force normally induced in said saturation winding by said alternating magnetic flux is substantially zero and being further disposed so that the magnetic flux created by each pair of windings located on either magnetic circuit traverses a closed magnetic path including the associated two independent legs but not said common leg, a first

5 output winding comprising two coils one disposed on each of the two independent legs of one of said magnetic circuits, said two coils of the first output winding being connected in series in such manner that any voltages induced therein by the action of said alternating magnetic flux are additive, a biasing winding effective when supplied with direct current to modify the control of said saturation winding on said one but not the other of said magnetic circuits and comprising two coils one disposed on each of the two independent legs of said one magnetic circuit, said two coils of the biasing winding being connected in series in such manner that any voltages induced therein by the action of said alternating magnetic flux will oppose each other and being so arranged that the magnetic flux created thereby opposes and substantially equals the magnetic flux created by the two coils of the saturation winding mounted on the said two independent legs of said one magnetic circuit whereby a voltage of relatively large magnitude will be induced in said first output winding when said saturation winding is energized, and a second output winding comprising two coils one disposed on each of the two independent legs of the other magnetic circuit and connected in series in such manner that any voltages induced therein by the action of said alternating magnetic flux are additive, said second secondary winding being characterized by the fact that a voltage of relatively high magnitude will be induced therein only when said saturation winding is deenergized.

4. In combination, a five-legged magnetizable core having two magnetic circuits each including one common and two independent legs, a primary winding disposed on the common leg of said core and constantly supplied with periodically varying current for setting up a primary flux in said core, a saturation winding disposed on the four independent legs of said core and supplied with unidirectional current for setting up a given condition of reluctance in each of said two magnetic circuits, a biasing winding disposed on a particular one of said magnetic circuits and supplied with unidirectional current for modifying the condition of reluctance set up in said particular one but not the other of said magnetic circuits by said saturation winding, an output winding disposed on said one magnetic circuit, and another independent output winding disposed on said other magnetic circuit.

5. In combination, a magnetizable core having two magnetic circuits both linked by an input winding normally supplied with alternating current, two control windings on said core one for varying the reluctances of both of said circuits and the other for varying the reluctance of one but not the other of said circuits, and two independent output windings one disposed on each of said two magnetic circuits.
